FEEDING ATTACHMENT FOR FLOUR-MILL ROLL FRAMES

Robert Linzberger, Sankt Gallen-Bruggen, Switzerland, assignor to Gebrueder Buehler, Uzwil, Switzerland, a Swiss firm

Filed Jan. 13, 1959, Ser. No. 786,517

Claims priority, application Switzerland Jan. 13, 1958
12 Claims. (Cl. 241—222)

My present invention relates to improvements in feeding attachments for flour-mill roll frames. Known feeding attachments generally have the disadvantage that the goods to be ground have to regulate or control the opening of the feed segment through a feeler and a lever system. Often a special attachment is provided for directing the goods from the feed segment into the grinding gap. The present invention discloses a much more simple construction in which the goods to be ground control the feed gap directly and which also comprises means for directing the goods into the grinding gap.

The feeding attachment disclosed by the invention is characterized by a movable shut-off wall of which the lower portion together with a feeding roll forms a feed gap. The feed gap, under the influence of the goods which press against said wall, is variable in size by turning said wall about an axis which is parallel to and lower than that of the feeding roll. This feeding attachment is further characterized by a baffle for directing the goods from the feed gap into the grinding gap, which baffle is disposed downstream of the feed gap and is secured to the lower portion of the shut-off wall.

One form of the invention and two modifications of certain parts thereof are shown in the drawing in which—

FIG. 1 is a section at right angles to the grinding rolls; FIG. 2 shows a detail of FIG. 1 in direction of the arrow II in FIG. 1; and FIGS. 3 and 4 each show a modification of certain parts of the mechanism shown in FIG. 1.

The housing 1 of the roll frame or stand contains two grinding rolls 2, 3 which form a grinding gap 4. The goods to be ground are fed into gap 4 by a feeding roll 6 disposed in the lower portion of a feed chamber 7. The latter is defined on one side by a fixed rear wall 8 and, on the other side, by a movable shut-off wall 9 which is provided with supporting and reinforcing ribs 10. The lower portion of wall 9 together with feeding roll 6, forms a feed gap 12. The feed gap opening is variable by turning wall 9 about an axle pin 14 which is parallel to the axis of roll 6 and lower than gap 12. Downstream of the feed gap, a baffle 15 is secured at 16 to the lower portion of wall 9 for directing the goods into gap 4. Baffle 15 is shaped so that in all of its operative positions its spacing from roll 6 increases in the direction towards gap 4. This arrangement avoids the goods flowing under baffle 15 exerting an upward pressure on wall 9, as the latter's position only should depend on the goods in chamber 7.

Wall 9 and baffle 15 form a sharp edge 16 of which the spacing from roll 6 defines gap 12. In all of its operating positions, edge 16 is closer to the surface of roll 6 than is any other point on baffle 15. Hence, the flowing goods could not interfere with the adjustment of wall 9.

In order to balance the turning moment about pin 14, produced by the pressure of the goods in chamber 7 against wall 9, a regulating means is provided which comprises two arms 19, 20 pivoted on a pin 22 to a hanger 21 fixed to housing 1. Arm 19 carries a roller 24 which presses against the upper portion of one of the ribs 10. On a threaded portion 26 of arm 20 is movably mounted a weight 27. Arm 20 further carries a piece 28 traversed by a screw 29 for transmitting the turning moment of weight 27 onto arm 19.

In operation, the goods in chamber 7 press against wall

2

9 which under the action of weight 27 is turned about pin 14. When chamber 7 is more or less full, wall 9 may assume for example a position 31 shown by dot-and-dash lines in FIG. 1. Gap 12 then is relatively very wide, and there will be no bridge-building in chamber 7. When, on the other hand, chamber 7 is nearing depletion, the pressure against wall 9 is only slight, and gap 12 becomes relatively very narrow. This arrangement produces a uniform distribution of the goods along the entire length 10 of the rolls 2, 3. By moving the weight 27 on the threads 26 and by changing the angle between the two arms 19 and 20 by regulating the screw 29, the most favorable characteristic of the feeding attachment may be attained for any type of goods.

15 In the modification shown in FIG. 3, baffle 31 is pivoted to wall 9, its position being controllable by a screw 32 and being maintained with the aid of a spring 33. In operation, the direction of baffle 31 may thus be regulated.

In the case of goods having a low bulk or pouring 20 weight, the sensitivity of the attachment disclosed should be raised. This is done by shifting the center of gravity of wall 9 and the parts secured thereto behind axle pin 14 or rather downstream thereof. The goods then do not have to do any work for adjusting the wall 9, 25 since the latter's center of gravity does not have to be raised. A mechanism for regulating the center of gravity of wall 9 is shown in the modification of FIG. 4. In this modification, a weight 36 is movably mounted on a threaded bar 35 attached to wall 9. By adjusting weight 36 on 30 bar 35, the center of gravity of wall 9 may be controlled. Thus, with bar 35 and weight 36 added, the device of FIG. 1 may be regulated to effectively control the flow of low bulk materials.

What I claim as new and desire to secure by Letters 35 Patent is:

1. In a feeding attachment on flour-mill roll frames, having grinding rolls, a feed roll, a movable shut-off wall, the lower portion of said movable wall together with said feed roll forming a feed gap of which the width under the 40 action of the goods to be ground pressing against said wall is variable by turning said wall about an axis which is parallel to the feed roll and lower than the feed gap to increase the width of said feed gap in proportion to the weight of good pressing against said movable wall, and a baffle for directing said goods which have passed through said feed gap into the grinding rolls, said baffle being disposed downstream of the feed gap and being mounted on the lower portion of said wall.

2. A feeding attachment as set out in claim 1, in which 50 the spacing of the baffle from said feed roll is greater than the width of the feed gap.

3. A feeding attachment as set out in claim 2, in which said spacing of said baffle from said feed roll in all the operative positions of said shut-off wall increases in the 55 downstream direction.

4. A feeding attachment as set out in claim 3, in which the shut-off wall and the baffle form a sharp edge the spacing of which from the feed roll defines the feed-gap width.

60 5. A feeding attachment as set out in claim 4, in which the spacing between said baffle and said feed roll increases abruptly downstream of the feed gap.

6. A feeding attachment as set out in claim 5, in which the baffle is articulated to the shut-off wall, and means for 65 adjusting the relative position of said baffle and said shut-off wall.

7. A feeding attachment as set out in claim 1, in which 70 is provided control means for exerting a closing force on said shut-off wall, said force increasing as said feed gap opens.

8. A feeding attachment as set out in claim 7, in which said means comprises a weighted roller disposed on the

upper portion of the shut-off wall, said roller pressing against said wall.

9. A feeding attachment as set out in claim 8, in which said roller is secured to a first arm, said weight is secured to a second arm, said first and second arms being pivotally mounted on a common pin, and force transmission means intermediate said first and second arms. 5

10. A feeding attachment as set out in claim 9, in which the force transmission means comprises a screw mounted in a threaded portion of one of said arms and pressing 10 against the other of said arm, the angle between said arms being variable by turning said screw.

11. A feeding attachment as set out in claim 9, in which said weight is movably mounted on its arm.

12. A feeding attachment as set out in claim 7, in which means is provided for adjusting the center of gravity of said shut-off wall inclusive of the parts secured thereto to move said center of gravity relative to said axis wall.
